UNITED STATES PATENT OFFICE.

WALTER J. KENNEDY, OF GRAND RAPIDS, MICHIGAN.

VALVE.

No. 894,957.

Specification of Letters Patent.

Patented Aug. 4, 1908.

Application filed September 3, 1907. Serial No. 391,272.

To all whom it may concern:

Be it known that I, WALTER J. KENNEDY, a citizen of the United States, residing at Grand Rapids, in the county of Kent and State of Michigan, have invented certain new and useful Improvements in Valves, of which the following is a specification.

My invention relates to improvements in automatic valves of the class described and claimed in Letters Patent number 867,139, issued to me Sept. 24, 1907, and its objects are: First, to provide a valve with which the inflow pipe and valve may be situated directly opposite, and in alinement with the outflow pipe. Second, to provide for conducting gas, &c., to the main outflow pipe and to the outflow pipe that leads to the pilot light, by separate and independent channels, and, third, to provide a means whereby the inflow valve may be locked to the desired position. I attain these objects by the mechanism illustrated in the accompanying drawing, in which

Figure 1 is a longitudinal section of the valve on the line *y y* of Fig. 5. Figs. 2 and 3 are modified forms of the same. Fig. 4 is a plan of the plug of the valve detached from the barrel, and, Fig. 5 is a transverse section of the plug and the bearing portion of the barrel, on the line *X X* of Fig. 2, with the plug turned around so that the slots for the passage of gas are closed and gas cannot pass through them.

Similar letters refer to similar parts throughout the several views.

This valve is constructed with a barrel *A* having a conical portion or opening for the reception of the conical plug *B*, and an opening leading therefrom for the passage of the stem *B'*, and at the large end a chamber *A'* is formed by the walls of the barrel, the large end of the plug *B* and the inner end of plug *E*. A revoluble valve *G'* is located in the bearing *G*, and so arranged that by turning it the passage *j* may be opened and closed at pleasure, and directly opposite from this valve is located the discharge pipe *C* having a small longitudinal aperture *c* through which gas may be allowed to escape from the chamber *A'*, when allowed to enter said chamber by the proper adjustment of the valve *G'*. The passage from the valve

G' to and through the chamber *A'* may be in any one of several ways, as for instance: In Fig. 1 I have shown the passage way *j* as extending directly to the center of the plug *B* and thence the longitudinal passage way *j'*, registering therewith and extending to the large end of the plug and opening into the chamber *A'* whence passage ways *b b*, in the periphery of the plug, extend back to position to register with corresponding passage ways *a a'* in the inner surface of the barrel with a small groove *b'* cut around the plug so that gas in the chamber *A'* may pass back through said passage ways to position to pass out through the passage way *c* in the outflow pipe *C*. In Fig. 2 the passage way *j*, passing through the valve *G'* and the side of the barrel *A*, opens directly into the passage way *a'*, which, in this case, is made to pass beyond the line of the passage way *j*, and thence through the registering passage way *b* to the chamber *A'*, and thence out through the passage ways *b—a* to and through the passage way *c* in the pipe *C*, to a gas burner or any other desired point, while in Fig. 3 the passage way *j* is made to pass through the valve *G'* forming a right angle, and an independent passage way *k* is formed to open from the valve *G'* into the chamber *A'* through the port hole *k'* whence gas may pass out through the passage ways *b b*, *a a'* and the groove *b'* that connects the passage ways *a a'*, to and through the passage way *c*.

D represents a lever that projects out at right angles from the stem *B'* and is provided with a passage way *d* that registers with the passage way *i'* in the stem, and is designed to convey gas from the valve *G'* to a pilot light located in any desired position. The passage way *i'* extends longitudinal of the stem *B'* to a position near the small end of the plug *B* where it passes through the side of the stem in position to register with the passage way *i* in the barrel *A*, which is designed to register with the small by-pass *g'* in the valve *G* so that gas passing through the passage way *j* will be diverted to the passage ways *i*, *i'* and *d*, as hereinbefore described. I have formed a short diverging chamber at *g* and at the end of the by pass *g'* so that if the valve *G'* is turned in the direction of the arrows in Figs. 1 2 and 3, sufficiently to cut off

the flow of gas through the valve G' into the barrel A, there will be sufficient passage way left at g' to allow gas to flow to the pilot light, as hereinbefore described, but these 5 offsets must not be so long as to prevent shutting both the passage way j and the by pass g' to prevent the flow of gas through either of said passageways, otherwise it would be impossible to cut off the flow of gas 10 when desired or necessary.

The grooves b' should be so formed as to avert all danger of forming shoulders or uneven places in the bearings between the plug B and the barrel A by the constant motion of 15 the plug when oscillating to open and close the passage ways a a, b b to regulate the flow of gas to the gas burner.

In Fig. 5 I have shown the passage ways a and b offset so that no gas can pass through 20 them, and to cause them to register so that gas may pass through, it is simply necessary to turn the plug B in the direction of the arrow in said figure, which is accomplished by pressing down upon the end of the arm D, 25 and the plug is forced back to normal position by means of a suitably adjusted spring, as F, in the chamber A', or in any other available position.

To insure the placing and holding of the 30 valve G' to the proper position to cause the passage way through the valve and the side of the barrel to properly register to allow the gas to flow freely through the barrel, to shut it off from the barrel and yet allow it to 35 flow through the passage way i i', or to close all passageways and shut off the flow of gas entirely, I place any available form of lever, as L', pivoted at l to the lever L so that the end l' may be made to engage the notch l" 40 that will hold the valve to the desired position, and for this purpose any available form of lever or catch may be used.

J represents a piece of the main line of gas pipe leading into the valve, and I represents a screw by means of which the flow of 45 gas through the arm D may be regulated and k" represents a screw designed to close the end of the passage way k so that gas cannot escape therefrom except as it passes through 50 the port hole k' into the chamber A', as hereinbefore described. H merely represents a packing box or nut designed to prevent gas from escaping through the barrel around the stem B'.

55 When the groove b' is made in both the surface of the barrel A and of the plug B it is desirable that they be so arranged that they will lap by each other a little so that there will be no danger of forming shoulders at the 60 lines of contact, or, in other words, so that there will be no lines of contact where a shoulder can be formed.

When the construction shown in Fig. 2 is

used the slots a' must be made large enough to insure a sufficient flow of gas to the chamber A', and the groove b' will only connect the several other slots, or, in other words, will allow the gas that has passed through the groove a' and its adjacent or registering groove b to the chamber A', to pass down through the several slots b in the plug that register with the slots a a in the barrel and thence through the passageway c. In Fig. 4 I have shown this construction of the groove b' in the plug B.

Having thus fully described my invention, what I claim as new, and desire to secure by Letters Patent of the United States, is:

1. In combination with a barrel having a conical inner chamber with longitudinal 80 slots in a portion of its surface, a tapering plug within said barrel having longitudinal slots in position to be made to register with the slots in the surface of the barrel and an annular groove connecting the longitudinal 85 slots, a hollow stem integral with the plug, and a hollow arm at right angles with the stem and in position so that the hollow in each will register with the other; an inflow pipe and cut off valve at one side of the barrel, an outflow pipe projecting from the other side of the barrel directly opposite from the inflow pipe and having passageways through the barrel and plug from the inflow pipe to the outflow pipe, the valve having a 90 by pass registering with the hollow in the stem, and a catch connected with the cutoff valve in position to lock this valve to the desired position.

2. In combination, a valve composed of a 100 barrel, a plug fitted into the barrel longitudinally and forming a chamber in one end of the barrel, an actuating spring in said chamber, an inflow pipe and an outflow pipe on directly opposite sides of the barrel with 105 passage ways formed from the inflow pipe longitudinally through the valve and back to the outflow pipe, a stem integral with the plug an arm at right angles with the stem each having a passageway registering with 110 the other, a cut off valve in the inflow pipe and having a by pass made to register with the passageway in the stem, and means for locking the cut-off valve to position.

3. In combination with a longitudinal barrel, a plug therein with longitudinal passage ways between them, an inflow pipe and an outflow pipe at right angles with and in direct alignment on opposite sides of the barrel, with passage ways formed to register with the passageways in the valve, a stem integral with the plug and having a passage way through it, an arm secured at right angles to the stem and having a passage way 120 registering with the passage way in the stem, 125 a valve in the inflow pipe having a passage

way to register with the passage way in the barrel and a by pass, with extensions, to register with the passageway in the stem, and means for latching this valve to the desired position to cause said passage ways to register, to partly register or to close, substantially as and for the purpose set forth.

Signed at Grand Rapids, Michigan, August 31, 1907.

WALTER J. KENNEDY.
